UNITED STATES PATENT OFFICE

JOHN H. SCHAEFER, OF GROSSE POINTE PARK, MICHIGAN

DESIGN FOR A CLOCK CASE

Application filed April 4, 1930. Serial No. 35,165. Term of patent 7 years.

To all whom it may concern:

Be it known that I, JOHN H. SCHAEFER, a citizen of the United States, residing at the city of Grosse Pointe Park, in the county of Wayne and the State of Michigan, have invented a new, original, and ornamental Design for a Clock Case, of which the following is a specification, reference being had to the accompanying drawings, forming a part thereof.

Fig. 1 is a front elevation of a clock case showing my new design, and Fig. 2 is a plan view thereof.

I claim:

The ornamental design for a clock case substantially as shown.

In witness whereof I sign this specification.

JOHN H. SCHAEFER
